UNITED STATES PATENT OFFICE

GLEN BUCK, OF EVANSTON, ILLINOIS

DESIGN FOR A PEN-HOLDING DEVICE

Application filed November 15, 1929. Serial No. 33,461. Term of patent 14 years.

To all whom it may concern:

Be it known that I, GLEN BUCK, a citizen of the United States, residing at Evanston, in the county of Cook and State of Illinois, have invented a new, original, and ornamental Design for Pen-Holding Device, of which the following is a specification, reference being had to the accompanying drawings, forming a part thereof.

The figure is an elevation of the pen holding device, showing the new design, the opposite side being identical in appearance as to design.

I claim:

The ornamental design for a pen holding device as shown and described.

In testimony whereof I have hereunto affixed my signature.

GLEN BUCK.
